UNITED STATES PATENT OFFICE.

SILAS M. FORD, OF ST. PAUL, MINNESOTA.

CORRUGATED LATH-BOARD.

1,207,389.

Specification of Letters Patent.

Patented Dec. 5, 1916.

Application filed May 25, 1916. Serial No. 99,819.

To all whom it may concern:

Be it known that I, SILAS M. FORD, a citizen of the United States, residing at St. Paul, in the county of Ramsey and State of Minnesota, have invented certain new and useful Improvements in Corrugated Lath-Boards, of which the following is a specification.

My invention relates to improvements in corrugated lath-board of paper or other fibrous sheeting designed to be fastened to the studding or beams of buildings to serve as a foundation for plaster. For such use it is desirable to make the board rather thick 10 in order to give it the requisite stiffness, and to render its plastering face waterproof in some suitable way. If the board is made of a single built up sheet as is now commonly the case, it is necessary to use for it a paper 15 board which is thick enough to give it body and which is at the same time sufficiently porous and absorbent to allow the water-proofing liquid to penetrate and be partially absorbed by it. The sheet is usually water- 20 proofed by passing it through a hot water-proofing liquid and squeezing out the surplus liquid before the sheet is corrugated or pressed to form. Paper which has the requisite qualities for such waterproofing is 25 expensive, and when the sheet is thick it takes up an unnecessarily large amount of the waterproofing liquid. Furthermore it 30 will become so impregnated with the liquid that its insulating properties will be much 35 impaired.

It is the object of this invention, among other things, to obviate the necessity of impregnating or using a thick absorbent sheet 40 by constructing the board with a comparatively thick or stiff unwaterproofed body sheet or sheets which need not be of absorbent material, and a thin outer or facing sheet which alone need be treated with the waterproofing liquid, thereby effecting a 45 saving in the cost of the sheeting, economizing in the use of waterproofing material and avoiding any considerable impairment of the insulating properties of the board.

More particularly the invention consists 50 in the construction, combination and arrangement of parts hereinafter described and claimed.

In the accompanying drawings, showing 55 an embodiment of the invention, Figure 1 is a perspective view of a fragment of the

improved lath board, and Fig. 2 is a cross section of the same on line 2-2 of Fig. 1.

As shown in the drawings, the board comprises a comparatively thick, corrugated body sheet 3 to give the board the necessary 60 stiffness and insulating properties, and a thin waterproofed outer or facing sheet 4 which overlies the sheet 3 on the plastering face of the board and is corrugated to conform to the corrugations of the sheet 3. The 65 facing sheet 4 is preferably of absorbent material so that it can be impregnated as well as coated with the water-proofing liquid applied to it, while the body sheet 3 which need not be, and preferably is not, 70 itself water-proofed need not be of absorbent material. In practice I have found it convenient first to pass the facing sheet 4 through a bath of water-proofing liquid in the usual way and then to lay the facing 75 sheet upon the body sheet and corrugate both sheets together, instead of one at a time. If this is done upon a machine wherein the board is fed between corrugating rolls, the two sheets can be fed to the 80 rolls together, the body sheet from one reel and the water-proofed facing sheet from another reel. It may be desirable to lay the facing sheet upon the body sheet while the 85 waterproofing is still warm and moist or sticky, so that the two sheets will adhere together when thus assembled.

The corrugations may be of any desired 90 shape and may be held to form by any suitable means such as the transverse strips 5 which are passed through the corrugations in the manner shown in my Patent No. 1,156,866 of October 12th, 1915, but it will be understood that I do not limit myself to the use of any particular means of 95 holding the corrugations to form.

Thus by the structure here shown and described I am enabled to use for the body of the board an under sheet thick enough 100 to give it the necessary stiffness which need not be waterproofed or of absorbent material, and for the face of the board to which the plaster is to be applied a thin waterproofed facing sheet, thereby attaining the 105 objects and securing the advantages above mentioned. I have spoken of the body sheet as a single sheet but it will be understood that it may comprise a pile of superposed sheets that are the equivalent of a single 110 unitary sheet.

I claim:—

1. A lath board consisting of a plurality of superposed sheets of fibrous material corrugated to form lath projections and intermediate depressions, said sheets including a body sheet to give the board the requisite stiffness and a thin waterproofed facing sheet overlying said body sheet upon the plastering face of the board.
- 10 2. A lath board consisting of a plurality of superposed sheets of fibrous material corrugated to form lath projections and inter-

mediate depressions, said sheets including a comparatively thick, non-waterproofed body sheet to give the board the requisite 15 stiffness and a thin waterproofed facing sheet overlying said body sheet upon the plastering face of the board.

In testimony whereof I affix my signature in presence of two witnesses.

SILAS M. FORD.
